US0D1017620S

(12) **United States Design Patent** (10) Patent No.: **US D1,017,620 S**
 Norman (45) Date of Patent: ** Mar. 12, 2024

(54) **DISPLAY SCREEN OR PORTION THEREOF WITH GRAPHICAL USER INTERFACE**

(71) Applicant: **Google LLC**, Mountain View, CA (US)

(72) Inventor: **Christopher Norman**, Brooklyn, NY (US)

(73) Assignee: **GOOGLE LLC**, Mountain View, CA (US)

(**) Term: **15 Years**

(21) Appl. No.: **29/826,148**

(22) Filed: **Feb. 9, 2022**

Related U.S. Application Data

(62) Division of application No. 29/703,754, filed on Aug. 29, 2019, now Pat. No. Des. 946,008.

(51) **LOC (14) Cl.** **14-04**

(52) **U.S. Cl.**

USPC **D14/485**
